ALONZO J. HALL, OF DERRY, NEW HAMPSHIRE.

Letters Patent No. 77,609, dated May 5, 1868.

IMPROVEMENT IN WATER-WHEELS.

The Schedule referred to in these Letters Patent and making part of the same.

TO ALL WHOM IT MAY CONCERN:

Be it known that I, ALONZO J. HALL, of Derry, in the county of Rockingham, and State of New Hampshire, have invented a new and useful Improvement in Water-Wheels; and I do hereby declare that the following is a full, clear, and exact description of the construction and operation of the same, reference being had to the annexed drawings, making a part of this specification, in which—

Figure 1 represents a top view of the device, with a portion of the gearing removed.

Figure 2 is a vertical section, taken at the line $z z$, fig. 1.

This invention consists of an inner reacting wheel, operating in conjunction with an outer wheel, together with a governor and valve for regulating the quantity and force of water. The inner wheel, A, is constructed with four arms, A^2 , through which the water is conducted to the outer wheel, B, the side of the arm on which the water is discharged forming a radial line, and the opposite side forming a tangential line, and the aperture through which the water is discharged forming a right angle with the radial line.

The effect of this peculiar construction is such that the water issuing from each arm impinges against two of the floats at once, and at such an angle as to produce greater effect than if the whole volume of water were directed against one float at a time.

The wheel A is made fast to the shaft by the flange D. An elevated portion of this flange, O, supports the hub of the outer wheel, B, which, resting upon O, revolves around the shaft. Through O there are small apertures, c, leading from a water-chamber, C, below, to a sunken circular groove in O. The object of this arrangement is to let the water pass from the chamber C through these apertures into the groove, and thus assist in supporting the hub of the outer wheel B, and thereby diminish the friction of this part.

The outer wheel, B, consists of a hollow cylindrical rim, to the inner surface of which are attached the floats, extending from the bottom of the rim upwards to the line $N N$, where there is attached to the inner surface of the rim a circular shelf, to which the floats are made fast at their upper edges, and which also prevents the water from flying upwards as it strikes the floats. Above this shelf are the spokes of the outer wheel, by which the rim is attached to the hub.

To each arm of the wheel A^1 is attached a governor, for the purpose of regulating the supply of water in case of a sudden diminution of the amount of labor, and a consequent diminution of the amount of power required. This governor consists of a weight, W, hung in adjustable bearings on the upper surface of the arm A^2 , and a gate, T, formed of a plate of metal, bent at a right angle, the longest portion sliding in a slot on the inner side of the aperture A^1 .

The weight W is connected by a rod to the gate T in such a manner that when the amount of power required is diminished, the centrifugal force occasioned by the increased velocity of the wheel will give the weight W a tendency to swing outward, forcing the gate T across the aperture A^1 , decreasing its width, and lessening the quantity and force of the water issuing therefrom. To prevent injury to any portion of the mechanism by such sudden revulsion, valves V, fig. 1, are attached to the upper surfaces of the arms of the wheel A, to allow the excess of water to escape.

The curb P is beneath the wheel around the lower part of the shaft, and has an outlet upwards, adjusted to the rim R, around the bottom of the opening in the wheel.

The water enters the curb at S, flows through the curb, and enters the water-chamber C in the inner and reacting wheel A. The water, by its upward pressure in this chamber, supports the wheel A wholly or in part, and thus diminishes the friction. Thence the water passes through the arms A^2 , and is discharged from the apertures A^1 , and strikes against the floats; and thus, by the action and reaction of the water, both the outer wheel B and the inner wheel A are caused to revolve, though in opposite directions. The water then falls in the free and open space beneath the outer portion of the wheel, and passes off.

Having thus described my invention, what I claim as new, and desire to secure by Letters Patent, is—

1. The apertures c and circular groove in flange O, in combination with the chambers C and hub of the outer wheel B, when arranged to operate in the manner and for the purpose specified.
2. The valve V, in combination with the weight W and gate T, substantially as and for the purpose specified.

ALONZO J. HALL.
